UNITED STATES PATENT OFFICE.

ENOS OSCAR WONDER, OF ALTOONA, KANSAS.

LABEL-HOLDER.

1,313,659.

Specification of Letters Patent. Patented Aug. 19, 1919.

Application filed March 25, 1919. Serial No. 284,888.

To all whom it may concern:

Be it known that I, ENOS O. WONDER, a citizen of the United States, residing at Altoona, in the county of Wilson and State 5 of Kansas, have invented certain new and useful Improvements in Label-Holders, of which the following is a specification.

This invention relates to holders adapted to be permanently secured to railroad cars 10 or other objects, for holding removable labels, or address cards or tickets; and it consists in the novel construction of the holders as hereinafter fully described and claimed.

15 In the drawings, Figure 1 is a front view of a label holder constructed according to this invention. Fig. 2 is an end view of the same.

The label holders are formed of thin sheet 20 metal, and each holder has a back plate 2 provided with a multiplicity of holes 3 which lighten it, and which permit the insertion of small tacks or nails by means of which the device is secured to the side of 25 a freight car or other object. These holes are spaced relatively near together and extend over the greater part of the back plate, but only a few of them are shown in the drawings. The back plate 2 is preferably 30 wider at its rear end than at its front or entrance end, and it has hook-shaped flanges 4 at its top and bottom edges. The back plate is provided with an open-ended notch 8 at one end, which permits the end 35 portion of the label to be seized by hand, and a tongue or flange 60 is formed at the bottom of this notch and projects upwardly at a right angle to the back plate. The

card or label 10 has a slot or hole 12 which is slipped over the tongue 60, and the 40 tongue 60 has a hole 61 through which a locking device 15, such as a snap-hook, is inserted. The locking device is attached to the back plate by a cord or chain 16 so that it cannot be lost. The card or label 10 is 45 sprung into and out of engagement with the tongue 60, and is slid in the retaining flanges 4.

What I claim is:

1. A label holder, comprising a plate provided at two opposite sides with retaining flanges for the label to slide in, said plate having also at one end a notch open at one end to permit the end portion of the label to be seized by hand, said plate having also 55 a tongue projecting at a right angle at the closed end of the said notch and adapted to engage with a hole in the label and prevent it from sliding in the retaining flanges. 60

2. A label holder, comprising a plate provided at two opposite sides with retaining flanges for the label to slide in, said plate having also at one end a notch open at one end to permit the end portion of the label to be seized by hand, said plate having also a 65 tongue projecting at a right angle at the closed end of the said notch and adapted to engage with a hole in the label and prevent it from sliding in the retaining flanges, and 70 a locking device engaging with the said tongue and holding the label in engagement with it.

In testimony whereof I have affixed my signature.

ENOS OSCAR WONDER.
